UNITED STATES PATENT OFFICE.

HARRY B. MILES, OF ELWOOD, VICTORIA, AUSTRALIA,

TALKING-MACHINE.

1,371,508.

Specification of Letters Patent.

Patented Mar. 15, 1921.

Application filed September 16, 1918. Serial No. 254,325.

To all whom it may concern:

Be it known that I, HARRY BENDA MILES, a citizen of the Commonwealth of Australia, and a resident of Elwood, in the State 5 of Victoria, Australia, and subject of the King, lieutenant Royal Australian Navy, have invented certain new and useful Improvements in and Connected with Talking-Machines, of which the following is a specification.

This invention has reference to improvements in means for reproducing sound in talking machines, particularly those of the disk type, and consists essentially in the employment upon one tone arm of two sound boxes or speakers and in mounting the same in such a way that the stylus of each box will repose in the same sound line and play on the same record simultaneously, the boxes 15 meanwhile altering position relatively to the tone arm. My improved mounting may also be used on one sound box with good results.

The two sound boxes can be mounted upon the tone arm in various ways but it is of 25 prime importance that the same shall be so connected and supported that a proper degree of flexibility of movement shall be possible for the boxes, as will be hereinafter explained.

30 One of the objects of my invention is to enhance the quality of the sounds reproduced and to reduce lateral friction between the styluses and the sound line as the tone arm and boxes move across the record.

35 At the present time most talking machines have a sound box fixed to the end of the tone arm through a flexible connection or goose neck, the stylus of the box being confined within the sound line and traversing the 40 record along an arc described by the tone arm. This does not conduce to best results in clarity of tone because the position of the box and attached stylus relatively to the groove in the record must needs change as 45 the box traverses the record. In other words, the sound box does not maintain the ideal positions relatively to the sound line, which should be in a line at right angles with a line joining the center of the record 50 and the stylus.

Attempts have been made to maintain such relative positions of the sound box and sound line and in one case at least has been effected by altering the shape and construction of the tone arm, which however, I wish to avoid, thereby making it possible to more 55

easily adapt my dual speaking or reproducing means to existing machines.

In the reproduction of sound from most records, the stylus inclines upon the same at 60 an angle of about 45°: if the sound box is not maintained or approximately maintained in its correct tangential position with the sound line, the stylus will be caused to incline unduly to one side or other of the 65 same which tends to destroy the record by wearing away the sound wave track and ultimately to distort the sound reproduced. If this can be avoided and the stylus kept as much as possible fairly in the sound groove 70 with its box substantially tangential therewith, the scratching sound common to these machines is reduced.

In this invention, I use two sound boxes which are mounted and connected to the 75 tone arm in such a way that the stylus of each shall be in the same sound line and preferably less than three quarters ($\frac{3}{4}$) of an inch apart. This is effected by using sound boxes of a type in which the fulcrum 80 of the stylus is mounted on the front of the box frame with the diaphragms of the boxes facing each other.

One way of mounting the boxes is by providing each with a rearwardly projecting 85 sound pipe that fits telescopically into or on a tubular connection or goose neck from the end of the tone arm which is capable of rotary movement in the T or end piece of the arm. The boxes should be locked together 90 in order that when one is lifted the other will be lifted with it, but each should be capable of a limited independent movement vertically.

The accompanying drawings illustrate 95 one mode of supporting and operating my dual speaker device, in which—

Figure 1 is a side elevation of the two sound boxes connected up to the tone arm of a talking machine, and 100

Fig. 2 is a plan view of same, the tone arm T-piece and connections being shown in section.

The tone arm 3 is of the ordinary and well-known type, into the T-piece of which 105 is fitted a liner 4 that is integral with one of the tubular extensions or goose necks. The other extension 5 is provided with an integral liner piece 6 that fits easily within the member 4. Attached to each sound box 110 7 is a short pipe 8 (hereinafter called the sound box pipe) that fits telescopically into

or on a tubular extension 5 which latter is curved or otherwise shaped between the tone arm and the boxes. The member 4 is capable of rotary movement in the said T-piece 5 and member 6 can turn freely in 4.

In order to permit the inner or left hand sound box 7 to move in a vertical plane within certain limits independently of its fellow, the liner 4 of the extension 5 is slotted transversely as at 9 in which a stud 10 that is on the liner 6 comes the stud limiting the rotary movement of the extension 5 in liner 4 until same is lifted clear of the record when both boxes will be moved together, as when they are to be laid over upon the tone arm to change the needles.

The boxes should further be connected together near to the tone arm T-piece and in line with the axis of the arm, through the brackets 11, one of which may be on the right hand box extension 5 and the other on the left hand box, each bracket connecting loosely with the common hinge pin 12 on a like bracket upon the other box. The curve of the tubular extensions 5 and sound pipes 8 has a radius centered on this pin 12 about which the boxes will swing, independently of the tone arm 3, as the latter moves over the record and the boxes travel 30 along the sound line. As the boxes alter their position in relation to the tone arm axis they will approximately maintain the correct tangential position with the sound line and thus keep each stylus fairly therein 35 and without serious inclination sidewise.

The boxes 7 should be arranged to converge toward each other at the front and each is placed on its mounting at an angle of about four (4°) degrees with the axis 40 of the tone arm, which has been found to give good results in practice. While it is not claimed that with two sound boxes each playing a record simultaneously, the boxes will traverse the ideal path, viz., the chord 45 of the arc described by the tone arm, it is claimed that by means of my invention a fuller tone is made possible with a reduction in the scratching sound.

It is important when using the dual 50 speaker device to insure that both boxes can be lifted off or placed upon the record at the same time. This movement is effected through the extensions 5 and their easy and flexible connection in the T-piece of the 55 arm 3. A further facility of movement of the boxes when following the sound line is imparted through the brackets 11, hinge pin 12 and the telescoping connections, which movement will be toward or away from the 60 tone arm axis. At the same time, a limited independent vertical movement of the boxes is permitted.

I have emphasized the importance of placing the styli less than three quarters ($\frac{3}{4}$) 65 of an inch apart: this is essential to avoid

echo, but in some reproductions such as band pieces, a wider distance between the needles is not a disadvantage.

Instead of the two separate sound boxes as I have described, a frame carrying two 70 diaphragms and styli can be employed, but this system is not so satisfactory as there is no flexibility between the mountings of the two diaphragms, and the styli cannot follow the sound line correctly if the 75 surface of the record is distorted or warped to any degree.

It will be evident that if one sound box is used with its extension 8 telescoping with the longer tubular extension or goose neck 80 5 and a bracket 11 is on the goose neck hinging with the bracket 11 on the box through the pin 12, the position of the box relatively to the tone arm will alter as it moves across the record. The box will, by 85 means of its flexible connections with the tone arm, be enabled substantially to adapt itself to its correct tangential position with the sound line as the record is played and thereby to keep its stylus properly in the 90 groove.

Having now described my invention what I claim as new and desire to secure by Letters Patent is:—

1. In a talking machine having a tone arm 95 and records provided with sound grooves, the combination of two sound boxes in pivotal relation to each other and attached to the tone arm, and styli on the two sound boxes, said styli and the sound boxes being 100 adapted to move with the tone arm and to move simultaneously across the record in the same sound groove of the record.

2. In a talking machine having a tone arm, the combination of two sound boxes 105 flexibly associated with the tone arm, both of said sound boxes being movable about a common axis at right angles to the longitudinal axis of the tone arm, the planes of the sound boxes being inclined to each other, 110 and means connecting the two sound boxes for moving each box upon movement of the other box.

3. In a talking machine having a tone arm, the combination of two sound boxes, 115 each sound box being provided with a tubular extension and each of the extensions being movably supported in said tone arm, the extensions being in telescopic relation to each other and being in communication 120 with the tubular tone arm, and means interconnecting both sound boxes and the tubular tone arm, said last named means being located outside the tone arm.

4. In a talking machine, the combination 125 with the tone arm of two sound boxes, a tubular telescoping connection between each box and the arm flexibly attached to the arm and a common pivotal connection between the boxes and the arm in the plane 130

of the longitudinal axis of the tone arm and at an angle to said axis.

5. In a talking machine having a tone arm, the combination of two sound boxes, tubular extensions on said sound boxes, the tone arm having a transverse tubular T-portion in which both extensions are telescopically supported, and means on said tubular extensions for preventing unlimited independent movement of said sound boxes about the axis of said T-portion.

6. In a talking machine having a tone arm, the combination of two sound boxes, tubular extensions on the sound boxes, the tone arm having a transverse tubular T-portion in which both extensions are telescopically supported so as to be rotatable about the axis of said T-portion, and a pivotal support for both of said sound boxes, said support being disposed at an angle to the axis of the T-portion.

7. In a talking machine the combination of a tone arm, a sound box, a tubular telescoping connection between the box and the tone arm flexibly attached thereto and a hingeable attachment between the box and the arm in line with the longitudinal axis thereof.

8. In a talking machine the combination of a tone arm, a sound box, a short curved tubular sound pipe attached to and extending rearwardly from the box, a goose neck telescoping with said short pipe and flexibly

attached to the tone arm, brackets on the goose neck and sound box and a hinge pin 35 in the brackets in line with the tone arm longitudinal axis.

9. In a talking machine having a tone arm, the combination of two sound boxes, styls connected with said sound boxes and 40 having their free ends close together, and telescopic extensions connected to each box and in telescoping relation with each other, one of said extensions having a slot and the other extension having a pin taking into 45 the slot and movable therein.

10. In a talking machine, the combination with the tone arm of two sound boxes, tubular telescopic connections between each box and the arm and flexibly mounted the 50 one within the other in the T-piece of the arm, a short slot in one connection, a pin in the other taking into the slot, a rearwardly disposed bracket on each sound box, a bracket on one of the tubular connections 55 and a pin in line with the longitudinal axis of the tone arm and at an angle to said axis connecting all three brackets together, as specified.

In testimony whereof I have signed my 60 name to this specification in the presence of two subscribing witnesses.

HARRY B. MILES.
